RADIO PROGRAM APPARATUS

Ernest A. Zadig, New York, N. Y.

Application April 29, 1931, Serial No. 533,615

3 Claims. (Cl. 40—52)

My invention relates to radio receivers and particularly to means for indicating in conjunction with the receiver the principal programs available at a given time.

For this purpose I provide an abstract of the principal or leading broadcast programs and print this upon a carrier preferably in the form of a strip. This carrier is periodically moved automatically, for instance once an hour, to display in conjunction with the receiver the leading available items with either or both the station letters or the dial setting and the time at which that particular item will be available. This apparatus is preferably combined with the alternating current source which energizes the set. The program carrier may be driven in different ways, for instance, by means of a power actuated relay brought into action periodically by some form of a synchronous motor receiving its energy from the same source or power which actuates the set.

Fig. 1 is a perspective view showing one form of radio receiver with a program apparatus involving my invention.

Fig. 2 is a diagrammatic view of one form of the apparatus and the electric circuits.

Fig. 3 is a side view of one form of actuating mechanism for the program strip carrier.

Fig. 4 is a perspective view of a roll for use with such apparatus.

In a typical radio receiver the cabinet 4 would have some sort of loud speaker 5, tuning apparatus with a knob 6, an indicating wave length or frequency dial 7, a controlling switch 8 and a volume control 9. The construction and arrangement of such parts of the apparatus, however, are immaterial to my invention. The set will also be provided with a suitable source of power, such for instance as may be adapted to receive a tap or attachment plug 10.

The program apparatus includes a strip 11 constituting the carrier which has printed on it the principal programs arranged in groups, for instance, to cover successive periods of one hour each, as indicated in Fig. 4. This may also carry advertising matter such, for instance, as shown by panels 12, and the programs and advertising will be visible through an opening or openings such as 14 in the cabinet. For convenience in handling the carrier strip may be mounted on a roller 15 adapted to be mounted in the cabinet in a suitable manner. This program roll may be supported in a housing or frame 16 mounted within the main cabinet and accessible, for instance, through a door such as 17 at one side of

the cabinet. The carrier frame also has a wind-up shaft or roller 18 which is intermittently driven by suitable mechanism. The general construction and arrangement for supporting the program roller or reel and the wind-up shaft or roller may be adapted to installation as a unit together with the power mechanism for addition to or insertion in any form of cabinet.

In the arrangement shown a wind-up shaft 19 is driven periodically by the action of an electrical solenoid having the coil 20 and the movable core 21. I have illustrated the transmission mechanism as of conventional form including, for instance, a lever 22 connected to the solenoid core or plunger 21 and carrying a pawl 23 coacting with a ratchet 24 attached to the drum 25.

A pulley 26 attached to the drum 25 has a band 27 for driving the wind-up shaft 18. Drum 25 may have a suitable toothed or friction driving periphery for engaging the program strip to draw it downwardly. When the solenoid is energized it draws the armature or plunger downwardly and the pawl 23 slips over the teeth of the ratchet 24 without actuating the same. When the solenoid is de-energized the spring 28 will draw the lever 22 upwardly and the pawl 23 will then rotate the ratchet so as to feed the program strip the requisite amount. It will be understood, of course, that the dimensions in gearing are arranged to produce the necessary length of feed of the program strip at each actuation of the relay. The feed drum may also be provided with a thumb piece 29 to permit manual operation, especially for feeding in the end of the strip to the wind-up shaft 18.

In Fig. 2 I have shown conventionally a typical circuit and arrangement for such a system. Here the radio receiver proper is indicated diagrammatically at 30, receiving its power from the attachment plug 10 and having a switch 31 for turning on and off the set. It is, of course, understood that this switch 31 has the knob 8 for actuating it.

The solenoid coil 20 receives its power periodically from the main line through the plug 10. As the ordinary power supply may be 110 volts, it is desirable to step down to a lower voltage, say 6 volts, for actuating the relay. For this purpose I have provided a transformer 32 having its primary connected to the main line and having its secondary adapted to be connected to the relay through a switch having a stationary contact 33 and a movable switch member 34. The closing of the circuit through the relay is automatically effected by suitable means preferably

driven from the same source of power as the set. In this case I have shown diagrammatically a synchronous motor 35 driving a cam 36 through suitable gear reduction mechanism 37. The motor and gear mechanism are designed to operate at the standard frequency to which the set is adapted and to rotate the cam 36 once for each unit of time covered by the program unit, for instance one hour. A plunger 38 is interposed between the cam 36 and the switch member 34. The spring 39 may be employed to bias the switch member toward the open circuit position. The motor 35 will accordingly be rotating continuously at a uniform rate and will continuously drive the cam 36. As this cam has only one projection 40 the switch member 34 will be held in the open circuit position at all times except when the shoulder 40 of the cam reaches the plunger 38 and by means of this latter impels the switch member to the closed circuit position. This energizes solenoid 20 and retracts pawl lever 22.

When the plunger 38 snaps off the shoulder 40 of the cam, the circuit will be rapidly opened at a definite instant. This de-energizes solenoid 20 and allows the spring 28 to move the pawl lever 22 and feed the program strip so as to bring the next period of the program into view in the opening 14. As cam 36 continues to rotate, switch member 34 remains in the open circuit position until shoulder 40 is again reached.

It should be understood, of course, that a suitable motor might be provided to operate on direct current in place of the synchronous motor 35 and also that the transmission mechanism and switch mechanism may be of any suitable character. It will be seen, however, that the amount of power required to rotate the switch actuating member is extremely small. It is also preferred that the relay switch should be open most of the time so as to draw a minimum amount of power.

Instead of winding up the strip 11 on the drum or roller 18, it might be simply discharged from the drive roller 25, which of course furnishes a uniform feeding action. When the roller 18 is employed it will be understood that the feed is controlled by roller 25 and that the belt 27 must be allowed to slip.

In carrying out the use of the invention it will be understood that the program strip can be printed to cover any period of time, for instance, so as to carry the principal items covering the period

of a week so that a new roll of programs can be inserted say each week. As the program drive mechanism is operated all the time regardless of whether the set itself is on or off, it will be seen that the program available at any particular time will also be on display adjacent the tuning mechanism of the set. Such an arrangement insures a very convenient means for indicating the outstanding program features at any time.

I claim:

1. An automatic program indicator for radio programs comprising a movable printed sheet, a sight window, clockwork associated with said program indicator, and means operated by said clockwork for intermittently moving the printed sheet 15 past the aforesaid window at time periods corresponding to the customary time period of radio program features, the said sheet being printed with indications of the successive program features, and the said sheet moving means being arranged to move said sheet in synchronism with the times of the program features indicated thereon.

2. An automatic program indicator for radio programs comprising a movable printed sheet, a 25 sight window, driving mechanism associated with said program indicator, and means operated by said driving mechanism for intermittently moving the printed sheet past the aforesaid window at time periods corresponding to the customary 30 time period of radio program features, the said sheet being printed with indications of the successive program features, and the said sheet moving means being arranged to move said sheet in synchronism with the times of the program features indicated thereon.

3. An automatic program indicator for radio programs comprising a movable printed sheet, a sight window, driving mechanism associated with said program indicator, and means operated by 40 said driving mechanism for moving the printed sheet past the aforesaid window at time periods corresponding to the customary time period of radio program features, the said sheet being printed with indications of the successive program features and the respective stations, and the said sheet moving means being arranged to move said sheet in synchronism with the times of the program features indicated thereon.

ERNEST A. ZADIG.
